UNITED STATES PATENT OFFICE

ARTHUR L. GODDARD, OF CHICAGO, ILLINOIS, ASSIGNOR TO FLASHTRIC SIGN WORKS,
A COPARTNERSHIP COMPOSED OF FRED PARKER AND HARRY S. PARKER, BOTH OF
CHICAGO, ILLINOIS

ELECTRODE

Application filed April 5, 1929. Serial No. 352,648.

This invention relates to improvements in electrodes for luminescent gas discharge lamps and tubes such as are now employed for electric advertising and display signs.

5 In the operation of these tubes, the electrical discharge within the tubes results in the bombardment of the electrodes by the positive ions set free from the atoms of the ionized gas. Under this action, which is very violent, small particles of the electrode material are shot with great force from the electrodes toward the surrounding wall of the outer glass tubes. To reduce the violence of this bombardment of the electrodes by the positive ions, I surround the electrodes with tubular glass shields which check the velocity of the approaching ions and reduce the excessive "sputtering" of the electrodes.

These shields, while they are supported in 20 the outer glass tube out of contact with both the electrode and the tube wall are subject to considerable heating first, from the electrodes which become hot from the bombardment above referred to and second from the 25 hot sputtered material deposited on them from the electrodes. The supports for these shields are usually in the form of seal tubes which extend into the outer tubes. The seal tubes also support the electrodes and provide 30 the vacuum seals for the outer tubes.

One object of my invention is to make the wall of the shield of a substantially uniform thickness particularly at the junction with the seal tube so that there are no unequal 35 sections in the shield wall to expand and contract differently and thus break or crack the shield particularly at the junction with the seal tube.

Another object of my invention is to make 40 the shield larger in diameter than the seal tube so that the shield may extend over the seal tube and be joined therewith at a point sufficiently removed from the electrode that the heat produced at the same during the formation of the tube and during its operation 45 will not crack or otherwise affect the junction between the shield and the seal tube.

A further object of my invention is to make 50 the seal tube relatively long so that the junction between the shield and the seal tube

will be sufficiently removed from the outer end of the seal tube that the heat used in fusing the outer end of the seal tube to the outer tube will not crack or otherwise affect the junction between them.

With relatively small electrodes, such as ones having an area not exceeding 1.5 square decimeters per ampere, the bombardment is distributed over the entire area of the electrodes due to the small size thereof, and 60 with the electrodes close to or in contact with the seal tube at its inner end, the heat caused by the bombardment is conducted to the seal tube. With the latter relatively long and having its tubular body open to the atmosphere at the outer end of the tube, such heat may radiate to the atmosphere and be carried off fast enough so that the seal tube will not be heated sufficiently to cause cracking of the juncture of the seal tube with the 70 shield or with the outer tube. Thus with my invention, the cracking hazard at the electrode ends of discharge tubes due to heat with small electrodes is minimized and the life of these tubes are greatly prolonged.

The invention consists further in the matters hereinafter described and claimed.

In the accompanying drawings—

Fig. 1 is a face view of an electric display sign, the characters of which are in the form 80 of gas discharge tubes having electrodes made in accordance with my invention;

Fig. 2 is an enlarged longitudinal sectional view through the electrode end of one of said tubes, taken on line 2—2 of Fig. 1; and

Fig. 3 shows the electrode unit before being inserted in the outer tube.

In the drawings 1, 1 indicate the luminescent gas discharge tube characters of the sign, and 2 indicates the sign body on the outer side of which said tube characters are mounted and supported for display. Each tube character 1 consists of a single length of appropriate glass tubing bent to the shape desired and having enlarged and elongated 90 bulb-like end portions 3 at the opposite ends of the tube. The bulbs 3 are usually disposed at right angles to the body of the tube and extend into the sign body through openings 4 therein, as shown in Fig. 2.

Located in each bulb portion 3 is an electrode element 5 in the form of a relatively short piece or section of metal or other desired material through which the electric current is discharged into the tube 1 to ionize the gas confined therein. The gas employed may be neon or any other of the rare gases of the noble gas group which are used in these tubes for illuminating purposes.

- 10 The bulb portions 3 of each tube are sealed so that a low vacuum may be produced in the tube as required for tubes of this character. The seal at each end of a tube is made through the use of a seal tube 6 which is made separate from the tube and afterwards inserted therein in the preparation of the tube. (See Fig. 3.) The seal tube 6 has a diameter less than the bulb portion 3 so that the seal tube may be inserted therein. The seal tube is 20 also made of glass of the same character as the outer tube 1 and the two are connected together by fusing at the outer end *a* of the seal tube. The inner end of the seal tube 6 is closed by fusing to provide the vacuum seal 25 7 for the outer tube. Electric current for the electrode element 5 is carried thereto by the lead-in wire 8 which is sealed in the seal 7 and extends to and is connected with the element 5 and supports the same at the inner end 30 of the seal tube 6 as shown in Fig. 2. The wire 8 may be looped at the element 5 to better support the same.

Located in the bulb portion 3 about the element 5 is a tubular shield 9 made of glass of the character required and having a diameter 35 larger than the element 5 and the seal tube 6 so that the shield may fit about both of the same. The shield 9 extends over the seal tube 6 to a point well beyond the seal 7 and is 40 joined to the seal tube by fusing the two together beyond the seal. The tubular body of the seal tube 6 is made relatively long, as shown in Figs. 2 and 3, so that the junction of the shield 9 with the seal tube is removed 45 far enough from the outer end *a* of the seal tube that the heat used in fusing the outer end of the seal tube to the outer tube 1 when preparing the tube will not crack the junction between the two. This is an important 50 feature of my invention because it lessens the cracking hazard of the shields when joining the seal tube to the outer tube in the preparation of the latter.

In joining the shield 9 to the seal tube 6 55 beyond the seal 7, the junction of the two is far enough removed from the vicinity of the seal that the heat used in fusing the shield to the seal tube will not strain the previously made seal 7 and crack it as frequently happens when the shield is joined directly to the seal. This is another important feature of my invention because it lessens the cracking hazard of the vacuum seals when fusing the shield tube to its support.

With the seal tube 6 made relatively long,

as shown in the drawings, the electrode element 5 is far enough removed from the outer end of the seal tube that the heat generated at the element in the operation of the same will not crack the junction between the seal tube and the outer tube because the heat has a chance to escape through the long wall of the seal tube to the atmosphere through the open outer end of the seal tube before reaching the junction between the seal tube. This is 75 another important feature of my invention because it lessens the cracking hazard of the tubes when relatively small electrodes are used, which electrodes due to their small size have the bombardment distributed entirely over 80 them and thus generate much more heat than the so-called large electrodes.

The wall of the shield 9 has a substantially uniform thickness throughout the length of the shield so that there are no unequal sections 85 in the shield wall to expand and contract differently and break or crack the shield. A bulb is blown in the seal tube 6 beyond seal 7 so that the glass wall of the shield 9 may be kept substantially uniform to the very base 90 of the shield and thus avoid unequal sections in the shield wall which by their different rates of expansion and contraction would place unequal strains on the shield to crack it at its juncture with the seal tube. This is 95 another important feature of my invention because it prevents cracking of the shields and exposing the electrodes to excessive bombardment. The shield projects beyond the inner end of the electrode 5 and protects it 100 from excessive bombardment by checking the approach of the positive ions to the electrode 5.

My invention is particularly usable with small electrode elements of the size heretofore referred to as the heat generated at said electrodes is prevented from cracking the seals to put out the tubes. The leakage hazard with small electrodes is thus greatly minimized and the tubes given long life.

The details of structure and arrangement of parts may be variously changed and modified without departing from the spirit and scope of my invention.

I claim as my invention:

An electrode unit for luminescent gas discharge lamps, comprising a reentrant seal tube closed at its inner end to provide a seal, an electrode element at said seal, a lead-in wire sealed in said seal and connected to said element, and an open ended tubular glass shield surrounding the element and the seal and joined to the tube beyond said seal, said tube having a bulb blown therein beyond the seal so that the shield may be joined thereto with its wall maintained substantially uniform in thickness at its junction with the tube.

In testimony whereof I affix my signature.

ARTHUR L. GODDARD. 130
